HYPODERMIC SYRINGE BODY

Hans Christer Arvid Evers and Hans Gösta Enström,
Södertälje, Sweden, assignors to Aktiebolaget Astra,
Södertälje, Sweden, a company of Sweden

Filed Dec. 11, 1967, Ser. No. 9,723

Term of patent 14 years

(Cl. D83—12)

FIG. 1 is a front elevational view, with the plunger extended, of a hypodermic syringe body showing our new design;

FIG. 2 is a perspective view thereof, with the plunger retracted; and

FIG. 3 is a perspective view of the opposite side thereof, with the plunger retracted.

We claim:

The ornamental design for a hypodermic syringe body, as shown and described.
